Primary Examiner — John M Otte(74) *Attorney, Agent, or Firm* — Finnegan, Henderson, Farabow, Garrett & Dunner, LLP(57) **CLAIM**

The ornamental design for a display screen with graphical user interface, as shown and described.

DESCRIPTION

The claimed design is a registered trademark of Google LLC.

The Sole FIGURE is a front view of a first embodiment of a display screen with graphical user interface, showing the new design.

The broken lines of uneven length show the display screen and form no part of the claimed design.

1 Claim, 1 Drawing Sheet(56)
